UNITED STATES PATENT OFFICE

2,481,861

HEATING APPARATUS

Moritz L. Mueller, Columbus, Ohio

Application April 18, 1945, Serial No. 588,933

3 Claims. (Cl. 237—55)

1

This invention relates to heating apparatus and has particular reference to a heating system of the chimney furnace type as disclosed and claimed in my Patents No. 2,274,341, issued February 24, 1942, and Nos. 2,348,834 and 2,348,835, issued May 16, 1944. In fact, the present invention comprises an improvement upon the constructions as disclosed in said patents and has particular reference to a novel and extremely useful improvement in the construction for the heat exchanger part of the system. The present invention contemplates a construction for the heat exchanger which is calculated to increase the efficiency of the system and also to simplify the shipment of the parts therefor when in a knockdown condition.

Principal objects of the invention are to provide:

A new and efficient construction for a heating system of the chimney furnace type;

A new and improved construction for the heat exchanger thereof which is designed to increase the efficiency of the system;

A new and improved construction for the heat exchanger part of the system which is calculated to simplify and reduce the cost of shipping the parts thereof in a knockdown condition.

Other and further objects of the invention will be apparent from the following description and claims and will be understood by reference to the accompanying drawings, of which there are two sheets, which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings

Fig. 1 is a fragmentary, somewhat diagrammatic view, with certain parts shown in section, and illustrating one form of the invention;

Fig. 2 is a sectional view of a nested stack of parts as they may be assembled for shipping purposes and which form a part of the heat exchanger of the system;

Fig. 3 is a fragmentary view, partially in section, of a modified form of the invention;

2

Fig. 4 is an enlarged fragmentary sectional view of the damper and control arrangement of the modification illustrated in Fig. 3; and

Figs. 5 and 6 are plan views of the lower and upper parts, respectively, of the damper and control arrangement illustrated in Fig. 4.

Referring now to Fig. 1, there are illustrated fragmentary parts of a house which include space 10 to be heated forming part of the dwelling 10 which includes a floor 12, a ceiling 14, attic space 16, and a roof 18. A masonry chimney 20 extends upright to and above the roof of the building and has an atmospheric discharge for the products of combustion. The fuel burning means, in the present instance an atomizing type of oil burner 22, is operatively associated with a combustion chamber 24 formed in the lower part of the chimney 20. Controls for regulating and controlling the operation of the fuel burning means 22 according to any of the suitable arrangements as disclosed in my Patent No. 2,348,834 may be employed, or any other desired control arrangement may be employed so as to regulate the operation of the fuel burning means 22 so as to supply heat as desired to the space 10.

The interior of the chimney is divided into an air path 26 for the air to be heated and a combustion products path 28 for the flue gases, in the present arrangement the air path surrounding the combustion products path 28. The paths 26 and 28 are defined by the chimney 20 and a tubular heat exchanger 30 which is arranged within the chimney 20 and spaced from the walls thereof. The lower end of the heat exchanger 30 is connected to a combustion chamber 24 so as to receive the heated products of combustion and may, as illustrated, be seated upon the upper rim of the walls which define the combustion chamber 24. The heat exchanger 30 extends vertically throughout the major portion of the length of the chimney 20 in spaced relation with the side walls thereof, preferably so as to define annular air path 26.

The upper end of the air path 26 is closed by a partition 32 which extends across the interior of the chimney 20 and is provided with a suitable opening through which the heat exchanger 30 extends. The partition 32 cooperates with the heat exchanger 30 to separate the air path 26 from the flue path 28. The heat exchanger 30 may terminate below the top of the chimney 20. The upper end of the air path 26 is provided with an air inlet opening 34 through which an electric motor operated blower 36 supplies air to the upper end of the air path 26 and under pressure so as

to cause such air to flow downwardly through the air path 26 and over the surface of the heat exchanger 30. The air may be delivered through the opening 34 at one side of the heat exchanger 30 so that the air will tend to flow in a spiral downwardly through the path 26, thereby effectively absorbing heat from all surfaces of the heat exchanger 30.

The lower end of the air path is provided with an outlet 36 which communicates with a duct 38 which in turn communicates through branch ducts with warm air outlets, such as 40, discharging heated air into the space 10. The air inlet to the blower 36 is connected through suitable ducts 42, 44 and 46 to return air outlets, such as 48, from the space 10 to be heated so as to permit the recirculation of air from the space 10 through the heating system and ducts associated therewith for reheating the same in order to heat the space 10 to the desired extent.

The blower 36 is adapted to be operated automatically with reference to the temperature of the flue gases in the flue gas path 28, or the operation of the fuel burning means 22 so as to circulate air through the air path 26 in order to recover the useful heat from such flue gases.

In my aforesaid earlier patents, as well as in my Patents No. 2,361,643 and No. 2,361,644, issued October 31, 1944, there are shown several different control arrangements for regulating the operation of the blower, any one of which or any other desired arrangement may be employed.

The height of the chimney and the size of the flue path 28 are such as to produce a high potential draft through the combustion chamber 24 and the efficient combustion of fuel therein. It is to be understood that the pressure of the air in the air path 26 during the operation of the blower is greater than that of the flue gases in the path 28 so that if any leakage of the heat exchanger 30 should occur, such leakage will be of air into the flue path 28 and not vice versa, thereby avoiding contamination of the air path 26.

The heat exchanger 30, as illustrated, comprises a series of frusto-conical pipes 50, 51, 52, 53, 54, and 55 stacked one upon the other with the bottom edge of the upper one overlapping the upper edge of the lower one so as to produce an effective seal at each joint. It will thus be observed that the walls of the heat exchanger 30 slope inwardly slightly so as to obtain impingement of the flue gases on the walls of the heat exchanger 30. It will also be observed that the walls of the heat exchanger 30 taper outwardly from the inlet to the outlet of the air path 26 so as to provide good contact and wiping action between the air as it circulates through the path 26 and the outer tapered surface of the heat exchanger 30.

The pipe sections 50, 51, 52, 53, 54, and 55 may also be made of different gauge metal so that the lower sections 50, 51, etc., are of heavier gauge than the upper sections, the thickness of the gauge decreasing with the distance from the combustion chamber 24. The thickness of the pipe sections has been somewhat exaggerated in the drawings, but I have found that a variation in gauge of an 8-gauge black iron tapered metal pipe for the lower section 50 to a 22-gauge galvanized iron pipe for the section 55 may be employed. The variation in gauge, of course, will depend to some extent upon the length of the heat exchanger 30 and the capacity of the system.

In so far as the galvanized iron pipe is concerned, I have discovered that the porcelain-

coated pipe of this character now available commercially is quite suitable for use as part of the heat exchanger, particularly for the upper portions thereof. Thus, with the tapered tubular heat exchanger, the hot flue gases rising upwardly in the air path 28 and the down-flowing air in the path 26 will better wipe the surfaces of the exchanger 30, thereby more efficiently transferring heat therebetween.

10 In order further to promote the exchange of heat between the flue gases in the path 28 and the air in the path 26, a hollow pipe 60 closed at its ends may be arranged centrally of the heat exchanger 30 so as to force the flue gases flowing upwardly in the path 28 into good contact with the inner wall of the heat exchanger 30.

As furnaces of this type are not preassembled but the parts thereof are made and shipped to each particular job and there assembled during

20 the building of the chimney 20, the matter of shipping the parts economically is an important factor. I have found that the tapered pipe sections may, in their disassembled or knockdown condition, be nested in the manner illustrated in

25 Fig. 2 so as to provide an assembly of the heat exchanger for shipping which is compact and only a very small portion of the length of the heat exchanger in its form when assembled. Due to the tapered nature of the pipe sections,

30 each one thereof may be nested at least to a certain extent in the one therebelow, and in this manner the entire heat exchanger in its knockdown condition need for shipping purposes only to displace slightly more space than the longest 35 one of the sections. This not only contributes to saving in the matter of freight rates and packaging, but also makes it possible to conveniently assemble for each particular job in one convenient package all of the elements of the heat ex- 40 change section.

In the embodiment of the invention illustrated in Figures 4, 5 and 6, which is a modification of that disclosed in Figs. 1, 2 and 3, the feature of the tapered frusto-conical heat exchanger has 45 been retained in a modified form and the hollow pipe 60 in the previous embodiment has been utilized as the flue for a water heating system which is operatively associated with the chimney furnace in Figs. 3 to 6. In this modification, while

50 the construction of the heat exchanger 130 is different in some respects from that illustrated in Fig. 1, the same action is obtained although the two lower sections 150 and 151 of the heat exchanger may be cylindrical in form. In this

55 case, the pipe 160 which has the same function as the pipe 60 in the previous modification, is enlarged at its lower end 161 to provide a chamber in which a water heating coil 162 is arranged, such coil being operatively associated with a hot

60 water storage tank 163 of a hot water system of a dwelling for heating water and storing the same in such tank 163. The enlarged end 161 which forms the chamber for the water heating coil is in the form of a pipe, the lower end of which has 65 a damper and control arrangement as illustrated in Fig. 4.

A stationary valve member 165 is arranged in the form of a cap and seated upon the upper end of the lower section 150 of the heat exchanger

70 130. The valve member 165 is provided with two series of openings 167 and 169 as illustrated in Fig. 5, the series 167 comprising a number of holes arranged in an annular row adjacent the outer periphery of the valve member 165, while the 75 series 169 comprises a series of holes arranged in

a circle within the series 167. The upper valve member 168, as illustrated in Fig. 6, rests upon the lower valve member 165 and is rotatable thereon so as to align the openings 170 in the valve member 168 with either the series of openings 167 or the series of openings 169.

It will be observed that the pipe section 161 which forms the chamber for the water heating coil is of materially less diameter than the outer pipe section 151 which forms a part of the heat exchanger. The series of openings 169 register with the interior of the pipe 161 so that when the openings 170 are aligned with the openings 169, flue gases from the combustion chamber 124 pass upwardly through the pipe section 150 and thence through the openings 169 into the interior of the chamber in which the water heating coil is arranged for heating such coil, and thence upwardly through the flue 160 thereabove.

When the upper damper or valve 168 is set so that the openings 170 therein are aligned with the series of openings 167, the flue gases, instead of passing upwardly over the water heating coil, will pass through the space between the pipe sections 161 and 151, thereby by-passing or shunting the water heating coil out of the path of the flue gases. The upper damper 168 may be set so as to align the openings therein with either of the series of openings in the lower damper 165, or so as to partially expose both of said series of openings so as to permit the flow of flue gases not only through the water heating chamber but also directly through the flue path 128 between the pipe 160 and the heat exchanger 130.

When the damper control is arranged so that all or substantially all of the flue gases pass upwardly through the water heating chamber, there may not be much heat which can be recovered by the air flowing through the air path 126 in view of the absorption of heat by the water heating coil 162 and also due to the fact that the flue gases are flowing upwardly through the pipe 160. While the blower 136 may be allowed to operate at such time, particularly during the heating season of the year, it may be desirable when the chimney furnace is operated solely for heating water, such for example as during the summertime, to discontinue the operation of the blower 136 and to this end the circuit for the electric motor which drives the blower 136 may be provided with a manually operable cutout switch, such as illustrated in Fig. 3 of my Patent No. 2,348,835, the blower being normally automatically operable as previously described to circulate air through the air path 126 so as to recover heat from the flue gases. However, if the electric motor circuit is manually opened as just described, heat to an undesirable extent may accumulate in the heat exchanger 130 and in order to dissipate this heat without introducing it into the space to be heated, I have provided a thermostatically controlled damper 170 which controls a relief vent by-pass 172 between the air path 126 and the flue path 128 which leads to atmosphere through the opening in the top of the chimney.

This thermostatically controlled damper 170, which is illustrated largely diagrammatically, may be of the construction and operation according to the disclosure as shown in my Patent No. 2,348,835 and particularly in Figs. 4, 5 and 6 thereof. Generally speaking, the damper 170 is adapted to be opened so as to open the by-pass when the temperature of the air at the upper end of the air path 126 reaches a predetermined degree (preferably higher than that at which the

thermostatic switch for the motor circuit is set to close), as will happen when the operation of the blower 136 is cut out by opening of the manual switch.

5 The damper 170 is mounted upon a horizontal pivot 174 and when closed as illustrated in Fig. 3 is adapted to close the by-pass 172. However, when open it permits the by-pass 172 to vent the upper end of the air path 126 to atmosphere. To 10 permit the thermosiphonic flow of air through the air path 126 at such time, the lower end of the air path may be provided with an opening 176 normally closed by a pivoted damper 178 and which is arranged to be operated by the control 15 180 which shifts the damper 168 so that when the damper 168 is set to supply the flue gases to the water heating coil chamber, the damper 178 will be open. The damper 178 may also be arranged to be operated independently of the damper control 180.

20 The damper control 180 comprises a rod which may project from the chimney and have its inner end connected to the damper member 168 for shifting the same between its two positions in order to selectively control the amount of heat absorbed by the water heating coil 162.

25 While I have illustrated and described a preferred embodiment of my invention, it is to be understood that this is capable of modification and I therefore do not wish to be limited to the precise details set forth, but desire to avail myself of such changes and alterations which may fall within the purview of the following claims.

I claim:

30 1. Heating apparatus comprising an upright chimney having an atmospheric vent at the upper end thereof, and a combustion chamber at the bottom thereof, fuel burning means associated with said combustion chamber, a tubular heat exchanger connected at its lower end to said combustion chamber to receive heated products of combustion therefrom and extending upwardly through said chimney for a major portion of the length thereof and in spaced relation with the inner walls of said chimney, said heat exchanger cooperating with said chimney to provide a flue passageway and an air passageway in intimate heat exchange relationship with each other through said heat exchanger, a blower arranged for introducing air to be heated under pressure into the upper end of said air passageway and forcing such air downwardly through said air passageway in countercurrent heat exchange relationship with said flue gases, said air passageway having an outlet for heated air at its lower end, a tubular member arranged in said flue passageway in spaced relationship with said heat exchanger and for a substantial portion of the length thereof, a water heating unit disposed 40 in a lower portion of said tubular member, and a damper arranged at the lower end of said tubular member and constructed and arranged to direct said flue gases across said heating unit and through said tubular member in one position of said damper and to direct said flue gases around said heating unit and through said heat exchanger in another position thereof.

45 2. Heating apparatus comprising an upright chimney having an atmospheric vent at the upper end thereof, and a combustion chamber at the bottom thereof, fuel burning means associated with said combustion chamber, a tapered tubular heat exchanger connected at its lower end to said combustion chamber to receive heated products of combustion therefrom and extend-

ing upwardly through said chimney for a major portion of the length thereof and in spaced relation with the inner walls of said chimney, said heat exchanger cooperating with said chimney to provide a flue passageway and an air passageway in intimate heat exchange relationship with each other through said heat exchanger, a blower arranged for introducing air to be heated under pressure into the upper end of said air passageway and forcing such air downwardly through said air passageway in countercurrent heat exchange relationship with said flue gases, said air passageway having the outlet for heated air at its lower end, said heat exchanger tapering inwardly in the direction of flow of flue gases and outwardly in the direction of said flow of air, a tubular member arranged in said flue passageway in spaced relationship with said heat exchanger and for a substantial portion of the length thereof, a water heating unit arranged in said tubular member, and a damper arranged at the lower end of said tubular member and constructed and arranged to direct said flue gases through said tubular member in one position of said damper and to direct said flue gases through said heat exchanger in another position thereof.

3. Heating apparatus comprising an upright chimney having an atmospheric vent at the upper end thereof, and a combustion chamber at the bottom thereof, fuel burning means associated with said combustion chamber, a tapered tubular heat exchanger connected at its lower end to said combustion chamber to receive heated products of combustion therefrom and extending upwardly through said chimney for a major portion of the length thereof and in spaced relation with the inner walls of said chimney, said heat exchanger comprising a stack of nestable frusto-conical pipe sections which cooperate with said chimney to provide a flue passageway and

an air passageway in intimate heat exchange relationship with each other through said heat exchanger member, said nestable pipe sections having a relation between the length, slope and wall thickness thereof such that sections of the same length will stack tightly within one another in the reverse order of their assembly in said apparatus and within the overall length of one of said sections, a blower arranged for introducing air to be heated under pressure into the upper end of said air passageway and forcing such air downwardly through said air passageway in countercurrent heat exchange relationship with said flue gases, said air passageway having the outlet for heated air at its lower end, said heat exchanger tapering inwardly in the direction of flow of flue gases and outwardly in the direction of said flow of air.
